UNITED STATES PATENT OFFICE.

JOHN W. McELHINNY, OF CHICAGO, ILLINOIS, ASSIGNOR OF ONE-HALF TO WILLIAM M. ROBERTS, OF OAK PARK, ILLINOIS.

TABLE AND KIT-CARRIER.

1,239,023.

Specification of Letters Patent. Patented Sept. 4, 1917.

Application filed November 5, 1915. Serial No. 59,829.

To all whom it may concern:

Be it known that I, JOHN W. McELHINNY, a citizen of the United States, residing in Chicago, in the county of Cook and State 5 of Illinois, have invented certain new and useful Improvements in Tables and Kit-Carriers, of which the following is a description.

My invention belongs to that general class 10 of devices known as tables and carriers and relates particularly to a combined table and kit carrier for the use of paper hangers, decorators and the like. While I have particularly mentioned paper hangers and deco- 15 rators, it may of course be used by mechanics engaged in other trades whenever found applicable. The invention has among its objects the production of a device of the kind described that is simple, convenient, com- 20 pact, rigid, durable and satisfactory. It has particularly among its objects the production of an extremely rigid table of more than average size that may be folded in small space for convenience in carrying, and 25 at the same time serve as a convenient carrier for the mechanic's tools or kit, as well as a work table when extended in operative position, which table may be further extended or enlarged for use on such occasions as 30 an even larger table may be desired.

To this end the invention consists in the novel construction, arrangement and combination of parts herein shown and described, and more particularly pointed out in the 35 claims.

In the drawings, wherein like reference characters indicate like or corresponding parts,

Figure 1 is a perspective view of the de- 40 vice folded for carrying;

Fig. 2 is a similar view of the device partially opened;

Fig. 3 is a side elevation of the table com- 45 pletely opened, with end extensions in place;

Fig. 4 is a top plan view of the table open, with a side extension in place;

Fig. 5 is an end elevation of the table with a side extension in place;

Fig. 6 is a sectional view substantially on 50 line 6, 6 of Fig. 5;

Fig. 7 is a sectional view substantially on line 7, 7 of Fig. 5, with the end extension in place;

Fig. 8 is a sectional view taken substan- 55 tially on line 8, 8 of Fig. 3;

Fig. 9 is a sectional view taken on line 9, 9 of Fig. 4;

Fig. 10 is a perspective view of one of the fittings, and

Fig. 11 is a sectional view substantially on line 11, 11 of Fig. 4.

Referring to the drawings. The table consists of top parts 1 and 2, suitably hinged together, each part consisting of one or more boards. The parts 1 and 2 are secured in 65 any suitable manner, the preferred construction being the hinge members 3 and 4, pivoted together at 5, the same being flanged and secured to the parts 1 and 2 respectively by bolts 7, plates 6 being arranged on the 70 top face of the table to prevent the bolts from being drawn through the boards. The boards are ordinarily made somewhat thin in order to afford lightness in carrying, and also since an excessive or considerable thickness of material is not needed in view of the light work done upon a table of this 75 kind.

Arranged at the free end of each top part is a flanged piece 8, 9, part 8 being secured 80 to the under side of the table top. The part is also preferably formed or bent at 10, 11 and 12 (see Fig. 10) to afford a convenient method of attaching the legs. I prefer to place a strip 13 at the end of each part, as 85 shown, to afford a convenient and durable engagement for the bolts 14 securing flange 8 to the table. These also reinforce the end of the table where the end extensions fit in, as will be more fully described hereafter 90 and prevent the top from warping.

The legs 15 are shown pivotally secured between parts 10 and 12 by bolts 16, or their equivalents for the purpose, the legs being of sufficient length so as to fold against the 95 hinge part or adjacent thereto at the center or inner ends of the top parts. To prevent the legs from folding and to make the table rigid when open, I provide braces 17 of any suitable form. In the preferred construc- 100 tion these are in two parts pivotally secured at 18 to each other and at 19 to the legs 15, and at 20 to the adjacent top part of the table. I have shown brackets 21 secured to the top part for conveniently securing the 105 ends at 20. Plates 18', or equivalents, arranged at the hinged connection 18 between the two parts 17, limit the movement of the braces 17 in open position, so that there is no tendency for the same to swing down past 110

the center to any great extent. They are preferably formed, however, so that the connection 18 of the brace is slightly past the center, as most clearly shown in Fig. 3, retaining the parts in operative position. I have shown the legs strengthened by cross bars 22, these being, of course, a matter of preference. With the preferred construction I provide two detachable extensions 23, one for each end, the same being formed with tongues 25 (see Figs. 2, 4 and 7) arranged to fit in recess 24, as shown in Fig. 7, between the flange 8 and the plate 13 at each end of the table.

In case it is desired to have a wider table than the top parts 1 and 2, as for example when working on wider wall paper, I provide an additional side extension 26 which may be detached when not desired. The extension 26 may be made of any suitable material and secured in place in any desired manner. I have shown it made of canvas secured to supports 27, which may be of wood or equivalent material. The same is of such size that when the canvas is substantially taut the supports 27 will lie against the ends 9. The same may be secured in place in any desired manner. For this purpose I have shown a bracket or part 28, having a bolt 29 extended therefrom, arranged to be engaged by a thumb nut 30 or the equivalent. A pin 31 (see Figs. 2 and 5) is also arranged on the parts adapted to fit in a hole 33, and prevent the outer end from dropping, 32 being the hole for the bolt 29 (see Fig. 2).

Any suitable means may be provided for locking the parts in closed position. For this purpose I have shown a catch 34 arranged to engage in a slot or opening 35 in the opposite part. The device is also shown provided with handles 36, by means of which the same may be carried when folded in going from one job to another. In Fig. 2 I have shown a brush 37, secured in a clip 38, and I have shown the canvas folded and arranged in one side. It may be mentioned that in addition to the extensions 23, which are shown folded in the case, and the brush and extension 26, that the mechanic may carry his overalls, shears, knives, straight-edge, rollers, etc., in the folded case.

After the mechanic has used his table and leaves the job he can fold the legs down, as shown in Fig. 2, place the various parts and tools in the carrier, fold the same and lock it. The device then to some extent resembles an ordinary suit-case. I have not shown any means other than the catch for locking the device, but, of course, a padlock or equivalent lock may be employed. The mechanic can then take his board, tools, etc., and conveniently carry them from one place to another, easily setting them up for use in but a moment's time.

It will be noted by referring to Figs. 1

and 2 that the center hinge parts 3 and 4 are provided with extensions 40, at each end, so that when the legs are folded the case is entirely inclosed by the top parts, the hinge parts 3 and 4, the ends 9 and legs, and presents a very neat appearance. The device is particularly convenient for use in cities where travel on street cars, or similar conveyances, is necessary, and where it is ordinarily inconvenient, and in some cases impossible to take a board on the car greater than six feet in length. Ordinarily it is desirable to use at least a seven-foot board, and most boards are made this length, and most of the paper hangers, therefore, have to cut off a foot from the boards, making a shorter board that is already none too long. With my device the table or board when folded is only about $3\frac{1}{2}$ feet long, yet the same may be extended to form a board of seven feet, and by placing on the extensions 23, a nine-foot or longer board or table may be had, this depending on the size of the parts. It is possible in addition that the table or board may be made wider for supporting one edge of an extremely wide paper. The decorator further does not have to bother about carrying board supports or legs, or as they are called, horses, which are cumbersome to carry, and his tools and clothes are securely packed so that he does not have to carry a grip or satchel besides the table. Many other objects and advantages of the construction herein described will be obvious to those skilled in the art.

Having thus described my invention, it is obvious that various immaterial modifications may be made in the same without departing from the spirit of my invention; hence I do not wish to be understood as limiting myself to the exact form, arrangement, construction and combination of parts herein shown and described or uses mentioned.

I claim—

1. In a table of the kind described and in combination, a suitable top, consisting of two parts arranged end to end, each provided with a downward projecting flange at each end, the adjacent flanges at the meeting ends of said top parts pivotally secured together, said flanges extending across the parts to the side edges thereof, the ends bent inwardly substantially parallel with the side edges, legs secured to the projecting flanges of the free ends of the top parts, braces connecting said legs with the table top parts, said legs of a length to extend adjacent to the center of the top when folded against the top.

2. In a table of the kind described and in combination, a suitable top, consisting of two parts arranged end to end, each provided with a downward projecting flange at each end, the adjacent flanges at the meet-

- ing ends of said top parts pivotally secured together, said flanges extending across the parts to the side edges thereof, the ends bent inwardly substantially parallel with the 5 side edges, legs secured to the projecting flanges of the free ends of the top parts, braces connecting said legs with the table top parts, said legs of a length to extend adjacent to the center of the top when folded 10 against the top and of a width corresponding with the width of said flanges, whereby when the legs are folded against their respective tops, and edge to edge against each other, the parts will constitute a closed case 15 with the top parts at the sides, the legs at the edges and the flanges at the ends, and means for securing said parts in folded positions.
3. In a table of the kind described and in 20 combination, a suitable top consisting of a plurality of parts, two parts arranged end to end, both parts provided with the projecting flange at each end, the adjacent flanges at the meeting ends of said two parts 25 pivotally secured together, said flanges ex-
- tending across the two parts to the side edges thereof with the ends bent inwardly substantially flush with the edge of the top part, a pair of legs for each part, having their outer ends pivotally secured at the 30 free end of the table top part to said inwardly bent ends, means for bracing said legs in an operative supporting position, said legs foldable against the under side of the top part, whereby the table may be 35 folded with the legs edge to edge between the two top parts, detachable top parts of a size to be contained within the folded table, means for securing the table parts in folded positions, carrying means secured to 40 said table and means arranged on the under side of the table top parts for securing tools thereto.

In testimony whereof, I have hereunto signed my name in the presence of two sub-
scribing witnesses.

JOHN W. McELHINNY.
